CARTRIDGE-SHELL.

1,103,202.

Specification of Letters Patent.

Patented July 14, 1914.

Application filed November 19, 1913. Serial No. 801,834.

To all whom it may concern:

Be it known that I, FRANK O. HOAGLAND, a citizen of the United States, residing at Bridgeport, county of Fairfield, State of Connecticut, have invented an Improvement 5 in Cartridge-Shells, of which the following is a specification.

This invention has for its object to produce a rim fire cartridge shell so constructed 10 as to provide an efficient gas check, without elongation of the shell and without expansion of the mouth of the shell.

It is of course well understood that all 15 properly constructed cartridge shells are adapted to be expanded in the chamber of the gun, by the pressure generated at the instant of the explosion, sufficiently to prevent the gases of the explosion from escaping rearwardly. Heretofore, so far as I am 20 aware, this gas check has been produced by expansion of the mouth of the shell against the chamber of the gun. It is furthermore well understood that unless guns are properly 25 cared for, and sometimes in spite of care, erosion of the wall of the chamber takes place near the mouth of the shell where the gases of the explosion escape into the chamber. This is especially likely to take 30 place in shooting galleries where the guns are not always well cared for and results in the mouths of the shells being expanded into the eroded portion of the chamber and locked there so that they can only be extracted with great difficulty. Furthermore, 35 the gas check is not effective owing to irregularities in the wall of the chamber so that in some cases the hot gases of the explosion will blow back into the face of the shooter.

40 These objections I wholly overcome and produce shells which provide an effective check against the rearward escape of gases, prevent the shell from sticking in the chamber (the chambers being always slightly 45 tapered) and furthermore eliminate the danger of the shells cracking, by stretching the metal of the shell, this for the reason that there is very much less resistance to the expansion or smoothing out of the stretched 50 portion of the shell than there is to the expansion of the unstretched metal at the mouth of the shell, and as the smoothed out portion of the shell is forced into contact with the wall of the chamber back of the

place where erosion ordinarily takes place 55 the gas check is sure to be efficient.

With the above stated and other objects in view I have devised the novel stretched shell which I will now describe, referring to the accompanying drawing forming a part 60 of this specification and using reference characters to indicate the several parts:

Figure 1 is a view partly in elevation and partly in section showing the rear end of a rifle barrel with a cartridge therein, and the 65 receiver; Fig. 2 a similar view after the explosion showing the stretched portion of the shell expanded against the wall of the chamber back of an erosion in the wall of the chamber; Fig. 3 an elevation of my novel 70 cartridge shell, and Fig. 4 is a section on the line 4—4 in Fig. 3, looking in the direction of the arrows.

10 denotes a rifle barrel, 11 the bore, 12 the chamber, 13 the receiver and 14 my novel 75 cartridge shell.

The essential feature of the invention is the stretching of the metal of the shell contiguous to the head, the effect of which is, when the shell is exploded, to cause the 80 stretched portion of the shell to be expanded or smoothed out and forced into contact with the wall of the chamber. 15 indicates where an erosion of the chamber has taken place through the escape of gases at the 85 mouths of shells. This erosion is greatest contiguous to the mouth of the shell and extends backward and forward from the location of the mouth of the shell but does not ordinarily extend backward more than a 90 third of the length of the shell, leaving the rear portion of the wall of the chamber in good condition, so that the engagement therewith of the portion of the shell contiguous to the head will provide an efficient 95 gas check, and obviate all danger from the rearward escape of gases. The stretching operation also obviates danger of the shells cracking. This stretching of the wall of the shell may be effected in any suitable 100 manner as by forming grooves or corrugations therein as indicated by 16.

The operation of my novel shell when firing takes place will be readily understood from Fig. 2. The stretched or expanded 105 portion of the shell near its head yields much more readily than does the unstretched mouth of the shell. The result is that the

mouth of the shell is not expanded at all but the stretched portion of the shell is expanded and smoothed out into contact with the wall of the chamber back of the eroded portion of the chamber, if there is any eroded portion, and provides an efficient gas check and moreover insures easy extraction of the shell.

Having thus described my invention I claim:

10 A rim fire cartridge shell having the metal of its rear portion forward of the head stretched and made thinner by forming de-

pressions therein, whereby the resistance of the shell to radial expansion is made less at the stretched portion than at the mouth of 15 the shell, the stretched portion remaining permanently expanded to provide a gas check.

In testimony whereof I affix my signature in presence of two witnesses.

FRANK O. HOAGLAND.
